PUMP

Filed July 5, 1928

UNITED STATES PATENT OFFICE

FRANK S. BARKS, OF ST. LOUIS, MISSOURI

PUMP

Application filed July 5, 1928. Serial No. 290,379.

This invention relates to pumps and with regard to certain more specific features, to pumps for barreled greases, oils and the like.

Among the several objects of the invention may be noted the provision of a high-capacity, grease pump for emptying storage tanks, barrels and like containers and adapted to be applied and adjusted to various sizes of said containers; the provision of a device of the class described in which the motorizing elements are readily removable from the pumping elements per se and the provision of a device of the class described permitting free lateral movement of the delivery line connected therewith. Other objects will be in part obvious and in part pointed out hereinafter.

The invention accordingly comprises the elements and combinations of elements, features of construction, and arrangements of parts which will be exemplified in the structure hereinafter described, and the scope of the application of which will be indicated in the following claims.

25 In the accompanying drawings, in which is illustrated one of various possible embodiments of the invention,

Fig. 1 is a vertical section showing the pump applied to a grease barrel;

30 Fig. 2 is an enlarged section showing certain details of motorizing and pumping elements;

Fig. 3 is a cross section taken substantially along line 3-3 of Fig. 2; and,

35 Fig. 4 is a cross section taken on line 4-4 of Fig. 2.

Similar reference characters indicate corresponding parts throughout the several views of the drawings.

40 Referring now more particularly to Fig. 1, there is illustrated at numeral 1 a steel barrel of the usual construction for shipping greases, oils and the like and which includes the conventional threaded bung opening 3

45 into which is threaded a closing cap (not shown). In the present invention a bushing 5 is threaded into the bung 3, said bushing 5 having a slideable and adjustable connection with the upper section 7 of a pump cylinder

50 9. A set screw 11 is used for maintaining a

given adjustment between the bushing 5 and pump cylinder 9, so that the suction end of said cylinder may be positioned at or near the bottom of barrels of various lengths.

The pump cylinder 9 is made in three sections, namely, said upper section 7 made of standard pipe which is small enough to pass through a standard size of bung 3 and bushing 5, a middle section 13 made of drawn tubing of a size which will pass through said standard bung 3 without the bushing 5 and a lower section 15 joined to the middle section 13 by a coupling 17. Tubing of smooth bore is used for the lower section 15, because it functions as a pump cylinder for a piston P, and corresponding tubing is used for the section 13 for convenience in making up the coupling 17.

The lower end of the cylinder 15 is provided with a suction foot valve 19 adapted to let grease into cylinder 15 but not out, and said piston P is provided with inwardly opening ports 21, normally covered by a valve plate 23 upon upward movement of the piston and uncovered by said valve plate 23 upon downward movement of the piston. The ports 21 and plate 23 with the associated valve parts form an outlet valve 25 which also comprises part of the piston assembly P. The piston P is hollow, thereby providing means for communication between the valve 25 and a hollow piston rod 27 which passes longitudinally through the pump cylinder 9 and emerges through a pump flange 29 by way of a stuffing gland 31.

Within the tube 13, the piston rod 27 is provided with a collar 33, welded or otherwise fastened thereon. Reacting between said collar 33 and said coupling 17 is a compression spring 35 serving purposes to be described and normally tending to push the piston rod 27 upwardly from its Fig. 1 to its Fig. 2 position.

It will be seen from the above that if the piston rod 27 is permitted to rise from its Fig. 1 position under expansive action of the spring 35 that the valve 25 in the piston will close, atmospheric pressure being assumed to be communicable to the interior of rod 27. An evacuation will thus be effected.

within the cylinder 15 and a consequent drawing in of grease will take place from the barrel 1 through the foot valve and into cylinder 15. If after this suction stroke or 5 any fraction thereof has been completed, the rod 27 be depressed against the action of spring 35, then the foot valve will close and the piston valve 25 will open so that the charge which was previously drawn into the 10 cylinder 15 will be ejected through the valve 25, the piston P and the hollow piston rod 27. The rod 27 is provided at its upper end with a T coupling 37 the latter being provided with a plug 39 for closing off the upper 15 end thereof. The arm of the T coupling 37 communicates with a flexible outlet hose 41 for delivering grease to a suitable point, such as mine cars or the like where large 20 quantities of grease are required in relatively loose bearings. It is not intended however to limit the invention to low pressure work inasmuch as it may readily be designed for high pressure operation, such as for lubricating automotive equipment.

25 The reciprocating movement of the hollow rod 27 is effected and controlled by a removable air engine, the lower flange 43 of which is removably held to said pump flange 29 by means of bolts 45. Spaced from the 30 flange 43 by means of spacer columns 47 is an air engine cylinder 49 in which is reciprocally movable a piston 51 having a piston rod 53 passing out of the lower end of the cylinder 49. The rod 53 is provided outside 35 of the cylinder 49 with a cross head 55 which is provided with a fork 57 for slidably engaging one of the spacer columns 47. The cross head also supports two rods 58 which pass slidably through the end of the cylinder 40 49 and are fastened into said pistons 51. The effect of the three rods 53, 58 and the action of the cross head is to prevent undesirable rotation of the piston assembly. It should be here noted that the plug 39 of the T coupling 37 merely abuts the lower end of the piston rod 53, so that for removing the air engine from the pump the only action necessary is to unbolt the flanges 29, 43, thus permitting of directly lifting off the engine 45 50 without otherwise affecting the pump. Independent turning of the rod 27 is thus also provided for.

55 The air engine is provided with air by way of a valve V fastened to the cylinder and having a port 59 communicating with a port 61 in the cylinder wall above the piston 51 in all positions of the latter. The port 59 is alternately covered and uncovered by a shoulder 63 on a valve stem 65, said shoulder being contiguous to an exhaust deflector 67. The end of the passage in which the valve stem 65 moves is used as an exhaust. Inlet of air is effected through a passage 69 across which moves a peripheral recess 71 alternating 60 65 with the covering and uncovering of the

exhaust port 59. An air hose 73 (Fig. 1) is used to bring air to the passage 69. No air inlet is provided beneath the piston 51.

Peripheral recesses 75 spaced apart the distance of the valve movement are cooperated with by spring pressed and sidewardly located ball detents 77 (Fig. 4) for providing positive full-stroke positioning of the valve. The nut 78 also functions as a stop against the valve body and a cup 80 screwed thereon. The valve 65 is provided with a stem 79 which is guided at its lower end in a hole through the engine flange 43.

70 In order to operate the valve, a bracket 81 is fastened to the rods 57 and reaches sidewardly to fork over a slidable washer 83 on the stem 79. Springs 85 are interposed between the fork washer 83 and stops 89 on the valve stem, whereby a driving connection is had between the bracket 81 and the valve 85 stem, such that the piston 51 may effect a full-stroke or such a fraction thereof as is desired before the valve changes position. This is due to the resilient action of the springs 85 which under the given adjustment are increasingly loaded as movement of bracket 81 advances, until the reaction of the respective spring 85 resets the valve at the end of the desired stroke. The length of the stroke of piston 51 may be varied by adjusting the positions of the stops 89.

90 Operation of the device is as follows:

The cap is unscrewed from the bung of the barrel and the bushing 5 substituted therefor. The set screw 11 is loosened so 100 that the foot valve may take up a position at or near the bottom of the container 1. The set screw is then tightened. By turning air into the passage 69 from hose 73 the piston 51 is caused to be pressed down so that the rod 53 thereof presses down on the plug 39 and forces the hollow piston rod 27 downwardly against the reaction of spring 35. This results in the foot valve 19 closing, and the charge in cylinder 15 being forced through valve 25, piston P, hollow rod 27, T coupling 37 and out to the hose 41 from whence it is delivered to the desired location.

105 After the piston 51 has descended to a predetermined position, the bracket 81 engages the lower valve spring 85 and after suitable compression thereof the spring causes reversal of the valve position and thereby closes the intake port and opens the exhaust port 59. The opening of the exhaust port releases the compressed air above the piston 51, whereupon the spring 35 is released so that it pushes the piston rod 27 upwardly against the engine piston rod 53. This action returns both the pump and the engine parts for another stroke. Air beneath the piston 53 is not trapped inasmuch as it leaks out at the unpacked bearing between the rod 53 110 115 120 125 130

and the cylinder end. The piston P in returning causes opening of the foot valve 19 and closing of the piston valve 25, thereby drawing another charge into the cylinder 15. 5 However, the charge already in the hollow rod 27 is unaffected.

It will be seen that one of the advantages of this construction is that the hose 41 may be pulled around through an arc of substantially 10 120° without straining it, because the rod 27 may turn independently of the engine rod 53 at the abutment between them.

The purpose of the gland 31 is to provide 15 for a possibility of leakage past piston P. Should the piston P become leaky it is possible that the space thereabove in the pump cylinder 9 would become filled up and that grease would flow out of the joint between 20 the pump flange 29 and rod 27. The gland 31 prevents this. Also a return port 91 is formed in the cylinder 9 so that the gathered grease may return to the container 1 instead of stopping the operation of the pump. It 25 is, however, quite probable that the piston P can be kept tight enough to prevent substantial leakage, and therefore eliminate the necessity for the gland 31 and port 91.

It will be seen that the ready removal feature 30 of the air engine permits of removing one defective engine and applying a perfect one without removing the pump per se from the container. This is of advantage in mine work where it is difficult to make repairs 35 where operations are carried on. The pump per se comprises a very simple mechanism and there is small possibility of it being deranged, especially in its protected position within the container.

40 It is to be understood that although the present engine piston and pump piston area ratio is four to one, that this may be increased or decreased so as to give higher or lower outlet pressures.

45 It is also to be understood that there is enough clearance between the bushing 5 and pipe 7 that air may enter the barrel to provide atmospheric pressure on the contained lubricant as the same is pumped.

50 In view of the above, it will be seen that the several objects of the invention are achieved and other advantages results attained.

As many changes could be made in carrying 55 out the above constructions without departing from the scope of the invention, it is intended that all matter contained in the above description or shown in the accompanying drawings shall be interpreted as illustrative and not in a limiting sense.

I claim:

1. A pump comprising a pump cylinder, a piston in the cylinder, a hollow piston rod for driving said piston, means for sucking 60 charges into the cylinder and discharging

them through said piston rod upon reciprocation thereof, means for reciprocating the piston rod comprising an engine for effecting a discharge stroke of the piston, a return spring for effecting a suction stroke of the 70 piston and a return stroke of the engine, said piston rod being independently rotatable for purposes of permitting lateral movement of its outlet.

2. A pump comprising a pump cylinder, 75 a piston in the cylinder, a hollow piston rod for driving said piston, means for sucking charges into the cylinder and discharging them through said piston rod upon reciprocation thereof, means for reciprocating the piston rod comprising a reciprocating air engine having a piston rod and a piston, means for removably fastening said engine to said pumping elements, the piston rod thereof abutting a portion of said hollow pump piston rod, whereby simultaneous reciprocation 80 of the engine piston rod and hollow pump piston rod may be effected but whereby the latter is independently rotatable of the former.

3. A pump comprising a pump cylinder, a piston in the cylinder, a hollow piston rod for driving said piston, means for sucking charges into the cylinder and discharging them through said piston rod upon reciprocation 85 thereof, means for reciprocating the piston rod comprising a reciprocating air engine having a piston rod and a piston, means for removably fastening said engine to said pumping elements, the piston rod thereof abutting a portion of said hollow pump piston rod, whereby simultaneous reciprocation 90 of the engine piston rod and hollow pump piston rod may be effected but whereby the latter is independently rotatable of the former, a full-stroke valve mechanism for the engine permitting intermittent application of air behind one side of the engine piston and intermittent release thereof and a return spring associated with the pump for 100 returning all reciprocating parts to their initial positions.

4. A pump comprising a pump cylinder and piston in the cylinder, a hollow piston rod for driving said piston, means for sucking 105 charges from the container into the cylinder and discharging them through said piston rod upon reciprocation thereof, means for reciprocating the piston rod comprising a reciprocating air engine having a piston rod and a piston, means for fastening said engine to said pumping elements, the piston rod thereof abutting a portion of said hollow pump piston rod, whereby simultaneous 115 reciprocation of the engine piston rod and the pump piston rod may be effected but whereby the latter is independently rotatable of the former, a full-stroke valve mechanism for the engine so connected and driven by the engine as to require non-rotation of said 120

125 engine as to require non-rotation of said 130

engine piston and piston rod, said valve mechanism causing intermittent application of air behind one side of the engine piston only and intermittent release thereof and a return spring associated with the pump for returning all the reciprocating parts to their initial positions.

5. A pump comprising a pump cylinder, a piston in the cylinder, a reciprocating hollow piston rod for driving said piston, means for effecting entrance of charges into the cylinder and discharging them through said piston rod upon reciprocation of the rod, means for reciprocating the rod and an articulation between said reciprocating means and the rod, permitting relative rotation between the two.

6. A pump comprising a pump cylinder, a piston in the cylinder, a reciprocating hollow piston rod for driving said piston, means for effecting entrance of charges into the cylinder and discharging them through said piston rod upon reciprocation of the rod, means for reciprocating the rod, an articulation between said reciprocating means and the rod, permitting relative rotation between the two, said piston rod having a laterally directed outlet for discharge purposes, said outlet being adapted to be adjustably directed because of said articulation.

7. A pump comprising a pump cylinder, a hollow, reciprocating piston rod extending into said cylinder, said rod having an outlet for delivery of fluid from said cylinder, an engine adapted to reciprocate the rod and an articulation between said engine and the rod permitting relative rotation between the two.

8. A pump comprising a pump cylinder, a piston rod reciprocating in said cylinder and extending therefrom, an engine pump adapted to reciprocate said rod and an articulation between the engine and said rod permitting relative rotation between the two.

In testimony whereof, I have signed my name to this specification this 26th day of June, 1928.

FRANK S. BARKS.
